W. A. HART

UMBRELLA CARRIER

Filed Sept. 10, 1921

Inventor
William A. Hart

By *C. C. Shepherd*
Attorney

UNITED STATES PATENT OFFICE.

WILLIAM A. HART, OF COLUMBUS, OHIO.

UMBRELLA CARRIER.

Application filed September 10, 1921. Serial No. 499,787.

To all whom it may concern:

Be it known that WILLIAM A. HART, a citizen of the United States, residing at Columbus, in the county of Franklin and State 5 of Ohio, has invented certain new and useful Improvements in Umbrella Carriers, of which the following is a specification.

This invention relates to an improved umbrella support adapted to be worn by those 10 whose occupations render it necessary or desirable that the hands should be kept free and unencumbered for the performance of various activities. Specifically, the invention aims to provide a supporting structure 15 adapted to be worn by postmen or others engaged in occupations of an analogous character for the purpose of enabling an umbrella or the like to be carried and to afford shelter from the elements without requiring the hands, thus enabling the wearer 20 to proceed in an unhampered manner with his tasks or activities and yet to be properly sheltered and maintained free from injurious exposure.

25 In accordance with the invention there is provided an umbrella support capable of being detachably worn upon the body of a wearer and formed to include a base structure capable of being secured by straps or 30 other adjustable means in a firm and positive manner around the body of the wearer, the said base structure being equipped with improved adjustable umbrella clamping and holding devices, which are capable of securely gripping and removably retaining 35 the staff of an umbrella in order that the latter may be stationarily situated above the wearer and prevented from losing its positions of application for service.

40 Among the objects of the invention are to provide the base structure with an improved strap arrangement capable of encircling the shoulders and waist of the wearer so that the said structure may be positively and securely 45 retained in its position of application around the clothing of the wearer; in providing the lower part of the base structure with a vertically adjustable clamping mechanism formed to include adjustable jaws 50 adapted to frictionally connect therewith the staff of umbrellas of varying size, shape and proportions and in providing the upper part of the base structure with a supplemental staff and to prevent movement there- 55 of when attached to the base structure, par-

ticularly during inclement weather wherein an umbrella may be subjected to considerable wind stresses.

With these and other objects in view, that will appear as the description proceeds, the 60 invention accordingly consists in the novel features of construction, combinations of elements and arrangements of parts, herein- 65 after to be fully described and pointed out in the appended claims.

In the accompanying drawing, forming a part of this specification, and in which similar characters of reference denote like and corresponding parts:

Figure 1 is a side elevation of the improved umbrella support comprising the present invention and illustrating the application thereof to the person of a wearer,

Figure 2 is a side elevation on a somewhat enlarged scale of the base structure,

Figure 3 is a vertical sectional view taken on the plane indicated by the line 3—3 of Figure 2,

Figure 4 is a transverse horizontal sectional view taken on the plane indicated by 80 the line 4—4 of Figure 2, and

Figure 5 is a detail sectional view taken on the line 5—5 of Figure 3.

Referring more particularly to the details of the invention and to the specific embodiment thereof shown, the numeral 1 designates my improved umbrella support in its entirety. This support is adapted to be detachably worn and includes a base structure 2, which in this instance consists essentially of a wooden panel of substantially rectangular formation, although this material and form are not strictly essential in carrying out the invention. The base structure is adapted to be strapped to the body 3 of the wearer and to this end the edges thereof adjacent to the bottom of the panel are formed with eyes 4, with which are connected snap links 5 carried upon the opposite ends of a waist encircling strap 6, the said strap including a buckle adjustment 7 by means of which it may be tautly drawn about the waist of the wearer. In connection with the strap 6, the top of the panel is formed with an eye 8, with which is engaged a snap hook or link 9, connected with a shoulder strap 10. This strap passes around the shoulder of the wearer, as shown in Figure 1 and has its lower portion looped as at 11 so as to be connected with the waist strap 110

6, a buckle construction 13 being situated in the shoulder strap so as to permit of its adjustment, as will be clearly understood. By this arrangement on the part of the straps 5 it will be apparent that the base structure may be securely and positively connected to the wearer in the position indicated and is capable of providing a rigid securing base for an umbrella which will relieve the wearer 10 of the necessity of effecting the support and manipulation of the umbrella. Further, the straps admit of adjustment to enable the same to be adapted to wearers of different size. The adjustment of the two buckles 15 provided in the straps is sufficient to effect the application or removal of the base. Carried by the strap 6 is a strap loop 13', which serves to hold an umbrella when not in use. This loop is so located that the umbrella can 20 be suspended in a convenient position.

To permit of the convenient attachment of an umbrella stand to the base structure, the latter is provided with a vertically disposed slot 14, covered substantially by a 25 metallic plate 15 in which a registering vertical slot 16 is provided. Arranged for vertical adjustment within the slot 14 is a nut 17 in which is threaded a lower clamping device 18. This device is in the form substantially of 30 a bolt and has its threaded shank positioned within the nut 17, the outer end of said device being formed to include resilient spaced staff gripping jaws 19 which are produced by longitudinally slitting one end of the 35 clamping device as indicated by the numeral 20 so that the outer end of said device will be substantially tapered when an umbrella staff 21 is positioned between said jaws. This construction is clearly shown in Figure 4 40 wherein it will be seen that by providing the shank of the device with a wing nut or its equivalent 22, the said jaws 19 may, upon the manipulation of the nut 22 be firmly forced into frictional gripping relationship with the staff 21 so that the latter will be securely supported in conjunction with the base structure. Moreover, the formation of the device 45 is such that the clamping jaws will be capable of operating efficiently irrespective of the varying proportions of the various umbrella staffs which are capable of being positioned therein. In fact, this feature of adjustability is found throughout my improved umbrella support, so that the latter may be 50 universally used under all conditions. A second wing nut 23 is also mounted upon the shank of the clamping device 18 and is adapted to be forced into frictional engagement with the outer face of the plate 15 and 55 to thus operate in connection with the nut 17 for maintaining the clamping device in any of its vertical positions of adjustment. It will be appreciated of course, that the 60 vertical adjustment of the clamping device 65 admits of corresponding adjustment on the

part of the umbrella engaged thereby, in order that the hood of the umbrella may be adjusted relatively to the head of the wearer.

In conjunction with the clamping device 18 it has been found advisable and desirable 70 to employ an upper supplemental clamp 24, which serves to stabilize the umbrella staff and to enable the attachment when in use to successfully resist high wind pressures or the like. The clamp 24 includes a rod 25 75 having a threaded end 26 capable of being positioned within a nut 27 longitudinally adjustable within a horizontal slot 28 provided in the upper part of the base structure. This slot is in part covered by a 80 metallic plate 29 in which is formed a horizontal slot 30 disposed for registration with the slot 28 and adapted to receive the shank of the rod 25, the said plate also serving to retain the nut in its position of application within the slot 28. A lock nut 31 may be provided upon the rod for engagement with the outer wall of the plate 29 which nut will serve to lock and retain the rod 25 85 in any of its horizontally adjusted positions. The outer end of the rod is equipped with a longitudinally adjustable sleeve 32 capable of being retained in an adjusted position upon said rod by means of a wing nut 33. The sleeve is formed with a resilient clasp 90 34, in which the intermediate portion of the umbrella staff 21 is capable of being readily secured and yet firmly retained, whereby through the cooperative action of the upper and lower clamping means the umbrella will 95 be securely supported in its position of use. The horizontal adjustment provided by the slot 28 admits of lateral adjustment of the hood of the umbrella so that the latter may be properly centered over the head of the 100 wearer.

In view of the foregoing description taken in conjunction with the accompanying drawing it will be apparent that the present invention provides a simple, useful and practical article for accomplishing the end set forth. The use of the device enables the wearer to secure the complete shelter afforded by an umbrella and yet to enable the hands to be employed in the pursuit of various activities without in any way being hampered in movement by the umbrella or associated structure. These cooperative features contribute toward the production of the successful features of use found in my 110 support and it is by their inclusion that the present construction is believed to constitute an improvement over devices heretofore proposed for this general purpose.

What is claimed is:

1. An umbrella support comprising a rigid panel, adjustable shoulder and waist straps operating to secure said panel to the body of a wearer, a vertically adjustable clamping means and a horizontally adjustable clamp- 120 125 130 135 140 145 150 155 160 165 170 175 180

- ing means carried by said panel for detachable connection with an umbrella staff.
2. An umbrella carrier comprising a panel, shoulder and waist straps connected with said panel for securing the latter to the body of a wearer, and vertically adjustable clamping means carried by said panel and capable of being rigidly yet detachably connected to the staff of an umbrella.
10. 3. An umbrella carrier comprising a base structure, adjustable shoulder and waist straps connected with said base structure for detachably connecting the latter with the body of a wearer, vertically adjustable clamping means carried by said base structure for engagement with an umbrella staff, and a superposed stabilizing clamp adapted for cooperation with an umbrella staff above said first named clamping means.
20. 4. An umbrella carrier comprising a base structure, flexible straps connecting said base structure to the body of a wearer, a vertically adjustable clamping means carried by said base structure and designed to frictionally connect an umbrella staff with said base structure, and a stabilizer connected with said base structure above said clamping

means and designed for engagement with said staff.

5. An umbrella carrier comprising a base, 30 securing straps connected with said base, spaced staff engaging clamping jaws carried by said base, means whereby said jaws may be maintained in various vertical positions of adjustment with respect to said base, 35 and a stabilizer connected with the upper part of said base and designed for engagement with an umbrella staff.

6. An umbrella carrier comprising a rigid base having a vertical slot provided therein, a clamping device vertically adjustable in connection with said slot and disposed for frictional connection with an umbrella staff, said base having a horizontal slot provided in the upper part thereof, a stabilizing clamp 45 horizontally adjustable in connection with said slot disposed for engagement with an umbrella staff above said clamping device, and straps connected with said base for removably positioning the latter upon the 50 body of the wearer.

In testimony whereof I affix my signature.

WILLIAM A. HART.
